England Bedding Company, Medford, Mass., a
corporation of Massachusetts

Application September 27, 1940, Serial No. 95,434

Term of patent 14 years

To all whom it may concern:

Be it known that I, Jacob C. Feldman, a citizen
of the United States of America, residing at
Boston, in the county of Suffolk and Common-
wealth of Massachusetts, have invented a new,
original, and ornamental Design for a Chaise
Longue or Similar Article, of which the follow-
ing is a specification, reference being had to the
accompanying drawing, forming part thereof.

Fig. 1 is a side elevational view of a chaise
longue embodying my new design; and

Fig. 2 is a front elevational view thereof.

The present design is characterized by the
relatively wide frame, substantially flush with
the sides of the mattress and having gradually
rounded corners at the junction of the seat and
back member, as shown by the solid lines.

The rear of the device is conventional and the
side not illustrated is similar to the side shown.

I claim:

The ornamental design for a chaise longue or
similar article, substantially as shown and de-
scribed.
